G. J. DORMANDY,

SHADE OR REFLECTOR AND SUPPORT THEREFOR.

APPLICATION FILED SEPT. 12, 1919.

1,371,549.

Patented Mar. 15, 1921.

UNITED STATES PATENT OFFICE.

GARRY J. DORMANDY, OF TROY, NEW YORK, ASSIGNOR OF ONE-HALF TO UNITED SHIRT & COLLAR COMPANY, OF TROY, NEW YORK, A CORPORATION OF NEW YORK.

SHADE OR REFLECTOR AND SUPPORT THEREFOR.

1,371,549.

Specification of Letters Patent. Patented Mar. 15, 1921.

Original application filed February 20, 1917, Serial No. 149,748. Divided and this application filed September 12, 1919. Serial No. 323,277.

To all whom it may concern:

Be it known that I, GARRY J. DORMANDY, a citizen of the United States, residing at Troy, Rensselaer county, in the State of New York, have invented certain new and useful Improvements in Shades or Reflectors and Supports Therefor, of which the following is a specification.

My invention relates to new and useful improvements in shades or reflectors and supports therefor, for use in connection with lamps, particularly electric incandescent lamps, wherein the lamp bulb is mounted on a member which is supported in such a manner that it may be adjusted or manipulated to locate the said bulb at the point most advantageous to the needs of the user. While the invention is capable of general application, wherever suitable, it is particularly adapted for use in connection with that general type of electric lighting fixture illustrated in United States Letters Patent granted to me No. 1,126,672, dated January 26, 1915, and No. 1,072,926, dated September 9, 1913.

In constructions of this general character, a lamp socket carrying the switch key is supported on a member which is adjustably mounted, and the reflector or shade is connected directly to the socket by a collar, or other suitable means. The result is, that operators, in adjusting the lamp to suit their necessities, grasp the reflector as a handle to swing the lamp supporting member, with the result that the thin sheet metal socket is twisted or bent, and often has its parts disengaged. It is, therefore, an important object of my invention, among others, to provide a shade or reflector which can be secured in operative relation to the lamp bulb engaged with the socket, by an improved support adapted to be connected to the adjustable supporting member, so that should an operator grasp the reflector to use the same as a handle to shift the supporting member, the force exerted will not be placed upon the socket or the lamp bulb, but will be exerted upon the adjustable supporting member, so

that the bulb and the socket are protected against strains or forces which would ordinarily injure the same.

My present application is a division of my prior application Serial No. 149,748, which was filed in the Patent Office on or about February 20, 1917, Patent No. 1,321,191, November 11, 1919, and relates particularly to a shade or reflector and a support formed integral therewith and to the novel arrangement by which the support is secured to the lamp support.

I have fully and clearly illustrated the present embodiment of my invention in the accompanying drawings to be taken as a part of this specification, in which drawings like reference characters indicate like parts, and in which Figure 1 is a view in elevation of an electric lighting fixture showing the present embodiment of my invention applied thereto; Fig. 2 is an enlarged view in side elevation showing the shade or reflector attached to the lamp support, the attaching portion of said shade or reflector being shown in side elevation; Fig. 3 is an enlarged view in side elevation of the shade or reflector and the support which is formed integral therewith, detached from the fixture; Fig. 4 is a cross section through the supporting member and lamp support of Fig. 2, and Fig. 5 is a detailed perspective of the clamping device which secures the support for the shade or reflector to the lamp support.

1 designates a hollow, vertical standard having laterally projected arms 2, which support joints 3 capable of movement in different directions, and for this reason may be termed "universal joints." One member 4 of these joints is provided with arms 5 having alining apertured ears 6, in which is slidably and rotatably mounted a hollow arm 33, supporting at one end a socket member 31 in which is received an incandescent lamp bulb 10.

At the head of the standard 1 may be arranged a distribution box 15, having a socket or sockets to receive the plug or plugs

16, to each of which is connected a conductor 17 entering one end of the member 33 and passing therethrough, and connected to the lamp in order to convey current to the latter. The distribution box has a suitable terminal for the feed wires 15^a which pass through the hollow standard 1. All of the features above described may be of the construction shown in my said patents, and need not be described in greater detail, particularly in view of the fact that my present invention is not limited to the specific construction of said features.

I will now proceed to describe the improved shade or reflector and support, constituting the invention covered by my present application. 29 designates generally a shade or reflector which may be made of thin sheet metal, and is preferably shaped 20 to conform to the general contour of the commercial form of incandescent lamp bulb, in connection with which it is adapted to be used, but the shade or reflector is of sufficient size so that when in position relative to 25 the bulb, it will bear the proper relation thereto, to give the desired reflecting or shading effects.

Extending rearwardly from the portion 30 is a longitudinally extending shank member 32, which is curved in cross section and adapted to have its concave side or face set 35 over the lamp supporting member 33. The reflector 29, the recessed portion 30, and the shank or securing member 32, are preferably formed in an integral piece from suitable sheet metal, and they may be provided with a marginal flange 34 which serves to stiffen the structure. In order to provide means 40 for securing the shank member or attaching member 32 to the member 33, I form parts of the flanges 34 on the opposite longitudinal edges of the member 32, by turning said flanges outwardly and backwardly, so as to be hooklike in cross section, as indicated 45 at 35, and employ a clamping member adapted to coöperate with these hooklike flanges to clamp the member 32 in position. This clamping member consists of a strip of metal 36, of substantially the same length 50 as the shank 32, and being curved in cross section to provide a longitudinal channel 37, whereby it may fit over the member 33 on the opposite side of the latter from the shank member 32. The opposite longitudinal side edges of the clamping member 36 are provided with in-turned hooklike flanges 38, adapted to interengage with the outwardly and backwardly turned flanges 35 on the member 32, so that when the 55 clamping member is in holding position relative to the shank a sleeve is formed surrounding the lamp supporting member 33. The clamping member is applied in engage-

ment with the shank by interengaging the flanges 38 at the forward end thereof, with 65 the rear ends of the flanges on the shank 32, and then sliding the clamping member longitudinally of the member 32 until it reaches the position shown in Fig. 2. In order to hold the sleeve thus formed rigidly in position, I provide a clamping screw 39 passing through an opening 40 in the bottom of the clamping member 36 and threaded through a nut 41 located within the channel of said member, said clamping 75 screw being adapted to impinge the member 33, whereby the members 32 and 36 are securely held in position. It will be seen that by impinging the screw 39 against the member 33 the member 36 is moved to cause 80 a positive interengagement between the flanges 38 and the flanges 35, whereby the shank 32 is positively clamped against the member 33. In order to prevent turning of the nut 41, the latter is arranged within a 85 groove or recess 42, arranged in the bottom of the member 36 and having parallel side walls 43, which the side faces of the nut engage, and the latter is held from turning.

It will be apparent that the shade or 90 reflector may be grasped and used as a handle to adjust the adjustable supporting arm without danger of deranging the lamp or its socket.

What I claim and desire to secure by Letters Patent of the United States is:

1. As an article of manufacture, a member comprising a portion formed as a shade or reflector and a portion integral with the first-named portion and formed 100 as a shank adapted to be fitted to a lamp support, said shank being provided with side flanges, and clamping means having flanges coöperating with the flanges on the shank for securing said member to the 105 support.

2. As an article of manufacture, a member comprising a portion formed as a shade or reflector and a portion integral with the first-named portion and formed as a shank 110 adapted to be fitted to a lamp support, said shank being provided with side flanges, clamping means having flanges coöperating with the flanges on the shank for securing said member to the support, and a clamping 115 screw passing through said clamping means and engaging the support to cause the flanges on the clamping means to hold said shank in place on the support.

3. As an article of manufacture, a member 120 comprising a portion formed as a shade or reflector and a portion integral with the first and formed as a shank adapted to be fitted to a lamp support, a marginal flange extending throughout said member, the 125 shank portion of the flange being bent back

upon itself, and a clamping member engaging with said flanges for securing said member to the lamp support.

4. As an article of manufacture, a member comprising a portion formed as a shade or reflector and a portion integral with the first and formed as a shank adapted to be fitted to a lamp support, a marginal flange extending throughout said member, the shank 10 portion of the flange being bent back upon

itself, and a clamping member having flanges turned back upon themselves and arranged to interengage with said shank flanges for securing said member to the lamp support.

GARRY J. DORMANDY.
